PLASTIC COATED FABRIC

Richard A. Mazur, Verona, Wis., assignor to United States Rubber Company, New York, N.Y., a corporation of New Jersey

Filed Aug. 21, 1963, Ser. No. 76,319

Term of patent 14 years

(Cl. D87—3)

The FIGURE is a plan view of a plastic coated fabric showing my new design. A single repeat of the design is included within the broken lines on the figure.

I claim:

The ornamental design for a plastic coated fabric, as shown and described.
